CORNICE

Bela B. Junkunc, Chicago, Ill., assignor to Bela B. Junkunc, Alexander Junkunc, Sr., Alexander Junkunc, Jr., and Joseph G. Junkunc, doing business as J. & J. Tool & Machine Co., Chicago, Ill., a partnership

Application June 16, 1949, Serial No. 99,521

3 Claims. (Cl. 160—38)

1

This invention relates to a cornice, and particularly to means for securing together two or more relatively narrow cornice members to form a wider cornice.

In accordance with the present invention a plurality of relatively narrow cornice members are vertically juxtaposed and the meeting edges are secured together by fastening elements which hold them together so that the front surface has the appearance of a unitary structure having the combined width of the individual members secured together. A decorative bead may be inserted between adjacent cornice members to provide a decorative effect.

One of the chief advantages of the vertically joined multiple cornice structure is the fact that it simplifies inventory problems. A single width cornice member carried in stock is sufficient to provide cornices of any desired width. The present disclosure is limited to cornices of fixed length, but it will be understood that the means for vertically joining the cornice members may be used just as well if the cornice members are adjustable in length. The cornice members will never separate accidentally after they are secured together, but may be separated readily if desired. It is also possible to add one or more cornice members to a cornice structure comprising two or more cornice members vertically joined in accordance with the present invention.

The structure by which the above and other advantages of the present invention are attained will be described in the following specification, taken in conjunction with the accompanying drawing of a preferred illustrative embodiment of the invention, in which:

Figure 1 is a fragmentary perspective view of a window trim including a cornice embodying the present invention;

Fig. 2 is a fragmentary rear elevation of the cornice shown in Fig. 1;

Fig. 3 is a cross sectional view, taken along the line 3—3 of Fig. 2;

Fig. 4 is a cross sectional view, taken along the line 4—4 of Fig. 3;

Fig. 5 is a detail perspective view of a pair of opposed clamping members in the position assumed in securing two cornice members together;

Fig. 6 is a fragmentary perspective view, partly in section, showing a cornice structure having a decorative bead inserted between the two cornice members;

Fig. 7 is a cross sectional view taken along the line 7—7 of Fig. 6; and

Fig. 8 is a fragmentary perspective view, partly in section, of a decorative bead.

2

In the drawings, the reference numerals 2 and 3 indicate a pair of cornice members vertically juxtaposed and clamped together to give the appearance of a unitary structure. The individual cornice members are identical, so only one will be described.

The cornice member comprises a metal plate having a substantially flat center portion 4 and end portions 5 curved uniformly to the rear to provide a pleasing appearance and to space the front of the cornice from the window without leaving a noticeable gap between the cornice and the end of the window. The front surface of the cornice may be smooth, but I prefer to have it fluted, as indicated at 6, to enhance its appearance. It will be understood that the cornice member may be flat throughout its length and it may be provided with any suitable ornamentation to give it any desired appearance.

10 The top edge 7 is bent back at right angles from the front of the cornice member and is then bent downwardly, as shown at 8, to form an inwardly extending flange spaced from the rear surface of the front of the cornice member a distance equal to the width of top edge 7. The bottom edge 9 is similarly bent to form a flange 10 vertically aligned with flange 8.

When it is desired to form a cornice structure of multiple width, two or more of the cornice members are juxtaposed vertically with the bottom edge 9 of one member on the top edge 7 of the member directly beneath it. If it is desired to provide an ornamental bead between the juxtaposed cornice members, a suitably designed member, hereinafter described, may be inserted between the said cornice members. The cornice members are secured together by means of a plurality of clamping members 11.

15 Each clamping member 11 comprises a substantially U-shaped clamp bulged out at its center and provided with an aperture 12 extending through the bottom and offset from its center. The clamping members fit around adjacent flanges 8 and 10 and are arranged in pairs with the apertures in each pair vertically aligned. The apertures are offset from the center so that a bolt 13 passing through both apertures will be outside flanges 8 and 10 and thus not pass through the juxtaposed edges 7 and 9 of the cornice members. This facilitates the joining of two cornice members because the clamping members 11 can be positioned at random along the length of the cornice members to be joined. The bolt is provided with a nut 14 so that the clamping members can be forced tightly together in

order to eliminate any gaps between the meeting edges of the cornice members.

If it is desired to break the continuity of the front surface of the cornice, a decorative bead 15 may be inserted between two juxtaposed cornice members, as shown in Figs. 6 and 7. The bead is flexible and may be of any suitable material, but is preferably made of plastic. The bead comprises a decorative bead portion 16, an intermediate web 17, and a fish tail shaped end 18. The bead is shown as being of elongated shape, but it may be of any desired shape. There may be one continuous decorative bead throughout the length of the juxtaposed cornice members or there may be a plurality of relatively small beads at spaced intervals, as desired.

The intermediate web portion 17 of the decorative bead acts in the manner of a gasket to take up any unevenness which may exist between the opposed surfaces of the juxtaposed cornice members. The fish tail shaped end causes a wedging action to take place as nut 14 is tightened on bolt 13 to force clamping members 11 together. This wedging action provides additional support for holding the front adjacent edges of the cornice members together.

Although I have described a preferred embodiment of my invention in considerable detail, it will be understood that the description thereof is intended to be illustrative, rather than restrictive, as many details may be modified or changed without departing from the spirit or scope of my invention. Accordingly, I do not desire to be restricted to the exact structure described.

I claim:

1. A cornice comprising a plurality of cornice members each having an inturned flange, the flange of one of said cornice members being juxtaposed on the flange of the adjacent cornice member, a U-shaped clamping member fitting around the flange of said one cornice member, a similar clamping member fitting around the flange of said adjacent cornice member, said clamping members each having an aperture offset from said flanges, said apertures being in alignment with each other, and fastening means ex-

tending through said apertures and holding said clamping members in clamping engagement with said cornice members.

2. A cornice comprising a plurality of cornice members each having an inturned flange, the flange of one of said cornice members being juxtaposed on the flange of the adjacent cornice member, a decorative bead having a web interposed between said juxtaposed flanges and a decorative portion projecting to the front surface of said cornice, a U-shaped clamping member fitting around the flange of said one cornice member, a similar clamping member fitting around the flange of said adjacent cornice member, said clamping members each having an aperture offset from said flanges, said apertures being in alignment with each other, and fastening means extending through said apertures and holding said clamping members in clamping engagement with said cornice members.

3. A cornice comprising a pair of separate cornice members, one of said cornice members being juxtaposed vertically on the other, a decorative bead positioned between said cornice members with a portion projecting in front of the joint between said cornice members, said decorative bead having a fan tail shaped portion extending at the rear surface of said cornice members, and clamping means for holding said cornice members and decorative bead together, said fan tail shaped portion wedging the rear edges of said cornice members when said clamping means is tightened.

BELA B. JUNKUNC.
